UNITED STATES PATENT OFFICE.

EUGENE W. HAWLEY, OF PHILADELPHIA, PENNSYLVANIA.

WARDROBE-TRUNK.

1,258,566.

Specification of Letters Patent.

Patented Mar. 5, 1918.

Application filed September 15, 1917. Serial No. 191,546.

To all whom it may concern:

Be it known that I, EUGENE W. HAWLEY, a citizen of the United States, residing at Philadelphia, county of Philadelphia, and 5 State of Pennsylvania, have invented a new and useful Improvement in Wardrobe-Trunks, of which the following is a full, clear, and exact description, reference being had to the accompanying drawings which 10 form a part of this specification.

The object of my invention is to provide a device for attachment to wardrobe trunks which will operate to retain in position the garments suspended in the trunk and which 15 will be held in operative position by means of its own inherent elasticity.

A preferred embodiment of the invention is shown in the accompanying drawings wherein—

20 Figure 1 is a perspective view of a wardrobe trunk, open, showing my invention applied thereto.

Fig. 2 is a top view of the garment hanging side thereof.

25 Fig. 3 is a vertical section on line 3—3 of Fig. 2, with the garment hangers omitted.

Fig. 4 is a partial front view of the showing in Fig. 3.

The trunk comprises two compartments 30 *a* and *b* hinged one to the other in the usual way, one compartment *a*, which is preferably the deeper one, being preferably provided with a hinged top *c*.

Secured to the inside of the upper edge 35 of the compartment *a* is a garment supporter, which may be of any suitable construction. I have illustrated one preferred form, the same comprising a flat metal bar *d* extending along the sides and rear of the

40 inside of compartment *a* and projecting somewhat above its upper edges, rods *e*, secured to and extending forward from the rear member of bar *d*, and rods *f* sleeved telescopically on rods *e*. The rods *e* and *f*

45 on each side constitute an extensible support for garment hangers *g*, which are suspended between the supports by means of end hooks *g'*.

Applied to the inside walls of opposite 50 sides of the trunk are metal angle bars *h*. These angle bars act as holders for the retainer hereinafter described. Each holder is secured at opposite ends and is L-shaped in cross section, the horizontal member of 55 the holder extending toward the wall, the vertical member of the holder being there-

fore spaced from the wall. Each holder is provided with a series of notches *i* which extend entirely across the horizontal member of the holder and part way up the vertical member of the holder. These notches are therefore open-ended at their lower ends and closed at their upper ends.

The retainer proper consists of a series of elastic spaced-apart strips *j* secured at 60 one end to a flat bar *k* and at their other end at the rear of the trunk, say to the rear member of the bar *d*. These strips may be made of any suitable elastic material. A high grade of suspender webbing is found serv- 70 iceable. The bar *k* is of a length substantially exceeding the distance between the holders *h* and preferably is of a length almost equal to the width of the trunk.

In operation, garments, hung upon hangers *g*, are suspended between the side supports *e f* while the latter are in extended relation. The hangers are then moved back and the rods *f* moved rearward on the rods *e*, thus shortening the supports to less than 80 the depth of the trunk. The bar *k* is then grasped with the two hands and moved down in front of the trunk beneath the holders (the strips *j* stretching to allow this movement) and is then moved rearward and 85 each of its opposite ends inserted in one of the notches *i* of the corresponding holder *h*. The elasticity of the strips *j* exerts a strong pulling force upon the bar *k* and holds it against the closed upper ends of the engaged 90 notches. The strips also operate to hold the garment hangers from sliding outward. The retainer is thus held in operative position by its own inherent elasticity.

To get access to the separate garments it 95 is only necessary to manually pull down the bar *k* of the retainer, thereby disengaging the bar *k* from the holders *h* and then withdraw the bar forwardly and throw the retainer over the top of the lid *c*, where it is 100 altogether out of the way.

Having now fully described my invention, what I desire to claim and protect by Letters Patent is:

1. In a wardrobe trunk, the combination 105 with one of the compartments of a trunk body and a garment supporter positioned therein, of a garment retainer secured at the rear of the compartment and adapted to extend over and in front of garments sus- 110 pended from the supporter, and holding means secured to the trunk beneath the

supporter and adapted to engage the retainer, the body of the retainer being of flexible and elastic material and adapted to be stretched to engage said holding means and to be held in fastening relation thereto by its own inherent elasticity.

2. In a wardrobe trunk, the combination with one of the compartments of a trunk body and a garment supporter positioned 10 therein, of a garment retainer secured at the rear of the compartment and adapted to extend over and in front of garments suspended from the supporter, said retainer comprising a body of longitudinally extending spaced apart flexible and elastic strips and an inflexible end bar to which the otherwise free ends of the strips are secured, holding bars secured to opposite side walls of the compartment and provided with series of notches in their lower edges, the end bar of the retainer being adapted to engage the holding bars by insertion in notches from underneath and being held in position therein by the upward pulling force of 40 the elastic strips of the retainer.

3. In a wardrobe trunk, the combination

with one of the compartments of a trunk body and a garment supporter positioned 25 therein, of a garment retainer secured at the rear of the compartment and adapted to extend over and in front of garments suspended from the supporter, said retainer comprising a body of longitudinally extending spaced apart flexible and elastic strips and an inflexible end bar to which the otherwise free ends of the strips are secured, 30 holding bars secured to opposite side walls of the compartment and provided with series of notches in their lower edges, the end bar of the retainer being adapted to engage the holding bars by insertion in notches from underneath and being held in position 35 therein by the upward pulling force of 40 the elastic strips of the retainer.

In testimony of which invention, I have hereunto set my hand, at Philadelphia, Pa., on this 13th day of September, 1917.

EUGENE W. HAWLEY.
